UNITED STATES PATENT OFFICE.

HENRY BAER, OF CINCINNATI, OHIO.

ENVELOP.

1,126,341.

Specification of Letters Patent.

Patented Jan. 26, 1915.

Application filed October 6, 1913. Serial No. 793,576.

To all whom it may concern:

Be it known that I, HENRY BAER, a citizen of the United States, residing at the city of Cincinnati, in the county of Hamilton 5 and State of Ohio, have invented certain new and useful Improvements in Envelops, of which the following is a specification.

The object of my invention is to produce a cheap, simple and efficient envelop.

It belongs to that class of envelops which are generally used for filing purposes, more particularly for holding and containing paper, documents, cards, deeds, wills, abstracts, bills and papers of this character which are 10 not placed in flat files; but, for purposes of expediency are preferably filed in special envelops for this purpose. Envelops of this character and in this class are, as a rule, made with folded sides, or double, or peculiarly 15 constructed so as to accommodate themselves to a varying number or multiplicity of filing papers which are inserted in them; they must necessarily be thus constructed as the ordinary envelops would hold 20 only a small number of papers, as, if too many are inserted, they (the papers) would either split or tear the envelop, or become folded and crumpled at the lower edge of the envelop, making it inconvenient to handle 25 the papers, and ruining their side edges, and their original neat and symmetrical appearance. These special envelops are also costly and take up more space than my envelop. The papers to be filed can be inserted 30 in my envelop more readily than in these special envelops, as they must to some degree be forced by the papers when they are inserted, whereas my new envelop yields readily to the documents as they are placed 35 in it, as its unique and peculiar construction adapts it to be spread or spaced evenly throughout its entire length and width, forming a practically perfect filing envelop.

Documents can be more readily examined 40 in my envelop, than in the ones now in use, as its peculiar top construction enables me to accomplish this examination readily and handily.

I make a self adjusting envelop which expands evenly to the extent of its contents. 45 Its various other features and advantages will readily become apparent from a perusal of the following specification.

In the accompanying drawing forming 50 part of this specification: Figure (1) is a plan view of the filing envelop blank; Fig.

(2) a perspective front view of the finished filing envelop; Fig. (3) a back view of the finished filing envelop, in elevation.

The body or front of the envelop is 60 marked (1), this body part has a recess or depression (2) cut in its top part and a flap (3) at its lower part; and two side flaps (4) and (5) disposed at the side thereof. The cut away part (2) lies between the 65 flaps (4) and (5) at the top of the envelop. When the blanks for these envelops are cut, the part cut out to form the recess (2), makes the flap (3) on the blank contiguous to the one being cut, so there is no waste in cutting 70 my blanks for the envelops. Flap (5) is first folded over onto the body (1) and then flap (4) is folded over the edge of flap (5), the gummed part (6) uniting the flaps (4) and (5). The flap (3) is then folded over 75 the lower part of the flaps (4) and (5), the gummed part (7) uniting the flap onto the flaps (4) and (5) and thus forming the bottom of the envelop. The gum (7) extends upon the flap (3) about half way, the 80 other half (8) being folded midway so that a spaced bottom as (9) is formed, see particularly Fig. (2).

When the envelop is finished cut away corners as (10) are present at the lower 85 outer edges and at the top the body 1 is so formed, by reason of the depression being cut in the top thereof, that retaining or guide edges as (12) are formed, inasmuch as the depression which is cut in the top edge does 90 not extend the entire width of the body of the envelop.

It will readily become apparent that by pressing the envelop on the side edges it will 95 open up evenly throughout its entire extent and thus enable the ready and satisfactory insertion of the filing papers.

The life of this class of filing envelop will also be prolonged.

I wish to be understood as not limiting 100 myself to the specific form of envelop herein set forth and described, as it is capable of considerable modification, as for instance the flap (3) may be made of any other form or contour and this would change the form and contour of the recess (2); the edges of the flaps (4) and (5) may be differently formed and shaped and the parts put together in any desirable manner.

What I claim as new and my invention 110 and desire to secure by Letters Patent is:

1. In an envelop of the character de-

scribed, said envelop consisting of a body portion, having side flaps folded over thereon and fastened together, and a bottom flap folded over onto the folded side flaps so that 5 it will extend below the bottom of the body portion and thereby form a bottom, the walls of which are spaced apart, the bottom flap being of less width than the body, so that, when folded, open cut off corner edges will 10 be formed, thus rendering the envelop expandible.

2. In an envelop of the character described, said envelop consisting of a body portion, said body portion being recessed 15 at its top so that side guard edges will remain, and having side flaps folded over

thereon and fastened together, and a bottom flap folded over onto the folded side flaps so that it will extend below the bottom of the body portion and thereby form a bottom, 20 the walls of which are spaced apart, the bottom flap being of less width than the body, so that, when folded, open cut off corner edges will be formed, thus rendering the envelop expandible. 25

In testimony whereof I affix my signature in presence of two witnesses.

HENRY BAER.
